UNITED STATES PATENT OFFICE.

JOHN Y. LINTNER AND LOURY L. BENJAMIN, OF BLAIRSVILLE, PENNSYLVANIA.

WRENCH.

1,095,005.

Specification of Letters Patent. Patented Apr. 28, 1914.

Application filed February 4, 1914. Serial No. 816,641.

To all whom it may concern:

Be it known that we, JOHN Y. LINTNER and LOURY L. BENJAMIN, citizens of the United States, residing at Blairstown, in the 5 county of Indiana and State of Pennsylvania, have invented new and useful Improvements in Wrenches, of which the following is a specification.

The present invention relates to improvements in wrenches, and resides in the construction, combination and operative arrangement of parts set forth in the following specification and falling within the scope of the appended claims.

15 In the drawing: Figure 1 is a side elevation of a wrench constructed in accordance with the present invention, Fig. 2 is a similar view with parts in section, Fig. 3 is a transverse sectional view on the line 3—3 of 20 Fig. 1, Fig. 4 is a similar section on the line 4—4 of Fig. 1, and Fig. 5 is a perspective view of the locking yoke.

Referring now to the drawings in detail, 1 designates the stationary head or jaw 25 which is provided with a shank 2. The shank, upon one of its faces, and at a suitable distance from the jaw 1, is channeled longitudinally its entire length, as indicated by the numeral 3. This channel is closed at 30 the end of the shank, through the medium of a filler 4, the said filler being in the nature of a rectangular block and is secured between the walls provided by the channel through the medium of removable elements, 35 in the nature of screws 5. The inner edge of the filler 4 is beveled or inclined, as indicated by the numeral 6, as is also the inner or connecting wall of the channel, the said wall or end being indicated by the numeral 40 7. The transverse wall formed by the channel 3, between the walls or ends 6 and 7 is provided with teeth 8.

The numeral 9 designates the movable jaw which is arranged for slidable movement upon the shank 2, the said jaw having one of its sides or its side engaging the smooth surface of the wrench opposite the channel 3 and its toothed wall 4, enlarged, or provided with a transverse extension 10, 50 whereby this portion of the jaw is afforded a greater bearing surface upon the shank 2.

The numeral 11 designates the locking element, the side arms of which having, what I will term, their upper ends, provided with a suitable registering opening 12 for the reception of a pintle 13, whereby

the yoke is secured to the jaw 9 to the opposite sides thereof, and at a point opposite the enlargement or extension 10. The side arms of the yoke are spaced to snugly engage with the opposite sides of the shank 2, and the connecting member 14 of the said side arms is provided with an opening 15 adjacent its lower corner, the said opening being provided to receive one end of a spring 16 which bears against the outer face of the shank. The side arms of the yoke, which may be indicated by the numerals 17, are provided, between their upper ends or ears, formed with the openings 12 and the 60 connecting member 14, with an integrally formed web 18, the said web being of a width corresponding with that of the channel 13, and being adapted to be received within the said channel, and what I will 65 term the inner edge of the said web is formed with teeth 20 which are adapted to coact with the teeth 8 in the channel of the shank 2. It will thus be noted that the web 18 is connected with the arms 17 of the 70 locking bolt only at the portions thereof adjacent the ears provided with the openings 12, a sufficient space being left between the sides 17 and the sides of the web to receive the side members of the shank provided by 75 the channel 3. As stated, the opposite edges of the sides are beveled, so that the connecting member 14 is disposed a considerable distance below the ears or corners of the yoke provided with the openings 12, and 80 when the spring 16 exerts a tension between the connecting member 14 and the shank 2, the teeth 20 of the web 18 will be forced into engagement with the teeth 8 of the shank. The opposite walls of the web 18 are arranged at an inclination similar to the walls 85 7 and 6, and the said walls 7 and 6 are adapted to serve as abutments for limiting the sliding movement of the locking yoke 90 in both directions.

From the above description, taken in connection with the accompanying drawing, the simplicity of the device as well as the advantages thereof will, it is thought, be perfectly apparent to those skilled in the art to 105 which such invention appertains without further detailed description.

Having thus described the invention, what we claim is:

1. A wrench including a head and a 110 shank, the said shank being channeled, the inner wall of the channel being formed with

teeth, a movable jaw upon the shank, a yoke pivotally connected with the movable jaw, said yoke having a web connected therewith, the said web adapted to be received within 5 the channel of the shank to engage with the teeth thereof, and a spring between the yoke and shank for forcing the web into engagement with the teeth of the shank.

2. In a wrench, a head provided with a 10 shank, said shank having a channel, the inner wall of the channel being formed with teeth, the end walls of the channel being beveled, a movable jaw upon the shank and having one of its sides enlarged, a yoke having 15 inclined side members pivotally connected with the movable jaw, said yoke having an integrally formed web, the opposite walls of which are inclined, the said web being spaced from the side members of the

yoke and adapted to be received within the 20 channel of the shank, the inner wall of the web being provided with teeth which are adapted to co-act with teeth in the channel, the connecting member for the sides of the yoke having an opening, a spring secured 25 within the opening and arranged within the yoke and adapted to bear against the shank to swing the yoke to bring the teeth of its web into locking position with the teeth of the channel. 30

In testimony whereof we affix our signatures in presence of two witnesses.

JOHN Y. LINTNER.
LOURY L. BENJAMIN.
